NITRATION OF OLEFINS

Thomas F. Doumani, Los Angeles, Clarence S. Coe, Rolling Hills, and Edward C. Attane, Jr., Inglewood, Calif., assignors to Union Oil Company of California, Los Angeles, Calif., a corporation of California

Application August 15, 1949, Serial No. 110,252

7 Claims. (Cl. 260—466)

1

This invention relates to the nitration of cyclo-olefines, and in particular concerns an improved process for preparing nitrogen oxide addition products of cycle-monoolefines, e. g. cyclohexene.

It is known that nitrogen oxide addition products of olefine hydrocarbons, particularly those of the aliphatic series, may be obtained by reaction between nitrogen tetroxide and the olefine under conditions of relatively low temperature. In general, however, such procedure is disadvantageous since it requires the use of highly purified reactants, one of which is usually employed in large excess, as well as special reaction solvents, and requires a reaction time of several hours to secure only very moderate yields of the desired product. It is also known to react olefines with nitrogen oxides in the vapor phase at temperatures as high as 160° C. Such procedure, however, gives rise to oxidation as well as nitration reactions and results in the formation of a mixed product comprising a variety of unstable nitrogen- and oxygen-containing compounds. Other means of nitrating olefines, as for example those in which nitric acid is employed as the nitrating agent, for the most part yield substitution products, i. e., products in which a nitrogen-containing group has been substituted for one or more of the hydrogen atoms of the olefine, the double bond being retained.

It is accordingly an object of the present invention to provide an improved process for the preparation of nitrogen oxide addition products of cyclo-monoolefines.

Another object is to provide a process whereby nitrogen oxide addition products of cyclo-monoolefines are readily prepared in good yield and in a high state of purity.

A further object is to provide an improved procedure for effecting reaction between nitrogen tetroxide and cyclo-olefines.

A still further object is to provide an improved method of preparing dinitro-cycloalkanes from the corresponding cycloalkenes, e. g., 1,2-dinitro-cyclohexane from cyclohexene.

Other objects will be apparent from the following detailed description of the invention, and various advantages not specifically referred to herein will occur to those skilled in the art upon employment of the invention in practice.

We have found that the above and related objects may be realized in a process whereby nitrogen tetroxide is caused to react with cyclo-monoolefines under conditions of moderately elevated temperature and pressure. In previously described processes for reacting nitrogen tetroxide

with straight- or branched-chain olefines, the violent nature of the reaction and the instability of certain of the products have dictated the avoidance of elevated temperatures and pressures, especially the latter. We have found, however, that cyclo-monoolefines may be reacted with nitrogen tetroxide at temperatures as high as 300° C. and under pressures as high as 100 atmospheres without running undue risk of explosion, particularly if the reaction be carried out in the presence of a solvent and in a continuous manner as is more fully explained herein-after. By operating under such conditions of moderately elevated temperature and pressure, the reactions whereby the desired addition products are formed take place relatively rapidly and are completed before undesirable side reactions, such as those involving oxidation, occur to any great extent. Operation under conditions which effect completion of the desired reactions in a relatively short time is further advantageous in that it permits the use of readily available reaction solvents, e. g., certain saturated hydrocarbons which ordinarily would be considered not suitable for such use because of their tendency to react slowly with nitrogen tetroxide.

As is well known, nitrogen tetroxide exists in equilibrium with its monomer, nitrogen dioxide, in accordance with the equation:

30

Accordingly, it is to be understood that where the term nitrogen tetroxide is employed herein and in the appended claims, such term refers to the equilibrium mixture of nitrogen tetroxide and nitrogen dioxide that exists under the prevailing conditions of temperature and pressure. Similarly, it is to be understood that while the process of the invention is described herein as applied to the nitration of cyclohexene, it is also applicable to the nitration of other cyclo-monoolefines as cyclopentene, methyl-cyclohexene, dimethyl-cyclopentene, cycloheptene, etc.

Considering cyclohexene as typical of the cyclo-mono-olefines, the main reactions involved in the process of the invention are believed to be as follows:

It is also possible, particularly under conditions favorable to oxidation, for other reactions to occur with the formation of various nitroso-nitro, nitroso-nitroso, hydroxy-nitro, bis-nitroso and other compounds, but by operating in accordance with the present invention the formation of such products is greatly suppressed so that the nitroso-nitro and dinitro compounds, particularly the latter, form the main products of the reaction.

The reaction between nitrogen tetroxide and cyclo-olefines according to the invention is carried out in the presence of the saturated hydrocarbon reaction solvent corresponding to the cyclo-olefine reactant. Thus, when the cyclo-olefine reactant is cyclohexene the reactant solvent is cyclohexane. Both reactants are initially dissolved in such solvent and the resulting solutions are separately preheated to approximately the desired reaction temperature before being contacted with one another. It is preferred that the reaction be carried out continuously with the cyclo-olefine maintained in the liquid phase and with concurrent flow of reactants.

When operating according to such preferred procedure, the initial solution of the nitrogen tetroxide reactant may be obtained simply by dissolving relatively pure nitrogen tetroxide in the saturated hydrocarbon solvent. It is usually desirable, however, to take advantage of the fact that nitrogen tetroxide is more soluble in saturated hydrocarbons than are its normally incident impurities, e. g., other oxides of nitrogen, air, ammonia, etc. Accordingly, the required nitrogen tetroxide solution may be obtained directly from the gaseous mixture obtained in the preparation of nitrogen tetroxide by the oxidation of ammonia by extracting such mixture with the saturated hydrocarbon solvent. The preparation of nitrogen tetroxide by the air oxidation of ammonia at elevated temperatures in the presence of a catalyst such as platinum gauze is a well known procedure and gives rise to a gaseous mixture comprising nitrogen tetroxide in admixture with other oxides of nitrogen, water vapor, unreacted air and ammonia, and other impurities. Instead of processing such mixture by low temperature distillation, absorption or other means to separate pure nitrogen tetroxide, the gaseous mixture may simply be contacted with the saturated hydrocarbon solvent, as for example in a countercurrent extraction tower, whereby the nitrogen tetroxide is selectively dissolved to form a nitrogen tetroxide solution directly suitable for use according to the present invention.

The olefine reactant may be derived from any convenient source, such as from petroleum refining operations or from other natural or synthetic sources. It may be employed in a relatively pure state or it may be in admixture with other olefines. In the latter case, mixed nitration products will be obtained. Also, if desired, the olefine may be in admixture with the corresponding saturated hydrocarbon. Thus, for example, a solution of cyclohexene in cyclohexane suitable for use in the present process may be ob-

75 tained directly by fractionally distilling a naphthenic petroleum extract or distillate to separate a fraction boiling at about 75°-85° C. The use of the saturated hydrocarbon solvent which corresponds to the olefine reactant is further advantageous in that should the solvent by any chance enter into the nitration reaction, the products thereby formed will be substantially the same as those produced by nitration of the olefine. Thus, in nitrating cyclohexene according to the process of the invention, employing cyclohexane as the saturated hydrocarbon solvent, certain of the possible products of reaction between nitrogen tetroxide and the cyclohexane are identical with those of the reaction between nitrogen tetroxide and cyclohexene. Ordinarily, however, little of the saturated hydrocarbon solvent will react with the nitrogen tetroxide before the reaction between the nitrogen tetroxide and the cyclo-olefine is substantially completed.

20 The manner in which the process of the invention is preferably carried out will be apparent from the accompanying drawing, the single figure of which represents a schematic flow sheet for the nitration of cyclohexene. Such mode of operation, however, is merely illustrative and is not to be construed as limiting the invention. Referring now to said drawing, a gas mixture comprising nitrogen tetroxide, obtained for example by the air oxidation of ammonia, is introduced through line 4 into absorber 2 at a point near the bottom, and cyclohexane is introduced into the upper portion of the absorber through line 3. Within absorber 2, the gas mixture rises countercurrent to the descending stream of cyclohexane whereby the nitrogen tetroxide is selectively dissolved. Non-absorbed gas leaves the absorber via line 6, and the solution of nitrogen tetroxide in cyclohexane is withdrawn from the bottom of the absorber and is passed through line 5 to pump 6 which supplies a pressure equal to that at which the reaction is to be carried out. From pump 6 the nitrogen tetroxide solution is passed through line 7 and heat exchanger 8, where it is heat-exchanged against the hot reaction product, and thence through line 9 to preheater 10. Within the preheater, which may take the form of a simple coil immersed in a molten salt bath, the temperature of the nitrogen tetroxide solution is raised to approximately the value at which the reaction is to be carried out. From preheater 10 the heated nitrogen tetroxide solution passes through line 11 into reactor 12.

30 The cyclohexene reactant enters the system through line 13 and is mixed with cyclohexane introduced via lines 3 and 14. The cyclohexene solution then passes through line 15 to pump 16 which supplies a pressure equal to that at which the reaction is carried out. From pump 16 the cyclohexene solution passes through line 17 to heat exchanger 18, where it is heat-exchanged against the hot reaction product, and thence through line 19 to preheater 20 which it is heated to approximately the desired reaction temperature. Preheaters 10 and 20 may conveniently be heated by a common heat source, as shown. From preheater 20, the cyclohexane solution is then passed through line 21 to reactor 12.

35 Within reactor 12, which may also take the form of a coil immersed in a molten salt bath, the nitrogen tetroxide and cyclohexene solutions are combined and reaction occurs under the applied temperature and pressure conditions as previously explained. The resulting reaction product is withdrawn through line 22 and passes

through pressure relief valve 23 to the heat exchangers 8 and 18 where part of its heat is given up to the incoming reactant streams. The product is then passed through line 24 to cooler 25 where it is cooled to substantially atmospheric temperature. From cooler 25 the product passes through line 26 into separator 27 where any non-condensed gases are separated and removed via line 28, and any water which may have been formed as a result of side reactions occurring is withdrawn through line 29. The crude product is then passed through line 30 into fractionator 31 where it is fractionally distilled to separate the cyclohexane solvent and the individual products of the nitration. As illustrated, such fractional distillation may yield an overhead stream of the cyclohexane solvent, a side-cut of nitro-nitrocyclohexane, and a bottoms fraction comprising 1,2-dinitrocyclohexane.

Considering the various steps of the process described above in somewhat greater detail, the absorption operation effected in absorber 2 is preferably carried out at temperatures below about 40° C. down to about -10° C. or below, and under superatmospheric pressure, e. g. from about 50 to about 500 p. s. i. g. Sufficient hydrocarbon solvent is employed to dissolve the bulk of the nitrogen tetroxide from the gas mixture. The absorber may be of conventional design, such as a packed or bubble-cap tower, and preferably operates on the countercurrent principle. The nonabsorbed gas removed at the top of the absorber may be discarded or it may be treated for recovery of valuable constituents. Thus, if it contains an appreciable amount of nitric oxide and/or ammonia it may be oxidized to form nitrogen tetroxide for use in the process or it may be treated by conventional methods for the separation of the valuable constituents. The solution of nitrogen tetroxide in the hydrocarbon solvent which is withdrawn from the bottom of the absorber is usually of a concentration suitable for use directly in the nitration reaction, i. e., about 10 per cent by weight. If desired, however, such solution may be enriched with nitrogen tetroxide or diluted with the hydrocarbon solvent to obtain solutions of greater or less concentration. Ordinarily, it is preferable that the nitrogen tetroxide solution employed in the process contain from about 5 to about 25 per cent by weight of nitrogen tetroxide, although more highly concentrated solutions may be employed with the less reactive cyclo-olefine reactants.

As an example of the operation carried out in the absorber, a gas mixture obtained by the air oxidation of ammonia and comprising about 6 per cent of nitrogen tetroxide, smaller amounts of nitric oxide, ammonia and water, and a large proportion of nitrogen is cooled to about 10° C. and compressed to about 100 p. s. i. g., and is passed countercurrent to a stream of cyclohexane in a packed absorption tower. The nonabsorbed gas withdrawn from the top of the tower contains about 1 per cent or less of nitrogen tetroxide and the bulk of the nitric oxide, ammonia, water and nitrogen, while the cyclohexane solution withdrawn from the bottom of the tower contains about 10 per cent by weight of nitrogen tetroxide. Such solution may be employed directly in the process herein described. Similar absorption processes may be carried out with other saturated cycloaliphatic hydrocarbon solvents employing the same or somewhat different conditions to obtain suitable solutions of nitrogen tetroxide. Alternatively, such solu-

tions may be prepared simply by dissolving relatively pure nitrogen tetroxide in the desired solvent.

As previously explained, the olefine reactant is likewise employed in the form of a solution in the corresponding saturated hydrocarbon solvent. Usually such solution is of approximately the same strength as the nitrogen tetroxide solution, e. g. from about 5 to about 25 per cent by weight, although more concentrated solutions may be employed, particularly when the cyclo-mono-olefine reactant reacts but slowly with the nitrogen tetroxide, and in some instances the solvent may be omitted entirely.

The conditions which have been found most suitable for effecting the desired reaction include a reaction temperature between about 40° C. and about 300° C., preferably between about 80° C. and about 200° C., and a pressure between about 2 and about 100 atmospheres sufficient to maintain the cyclo-mono-olefine and the solvent substantially entirely in the liquid phase. Usually the pressure will be between about 2 and about 20 atmospheres. It has also been found desirable to employ short contact times, e. g. from about 0.1 to 2 minutes, so as to minimize the formation of by-products either by side reactions between the nitrogen tetroxide and the cyclo-mono-olefine or by reaction between the nitrogen tetroxide and the saturated hydrocarbon solvent. As previously explained, by-product formation is further minimized as a result of employing as the solvent the saturated cyclo-aliphatic hydrocarbon corresponding to the cyclo-mono-olefine reactant.

In order that the contact time at the desired temperature may be readily controlled, the reactants are heated approximately to the reaction temperature, i. e., between about 40° C. and about 300° C., prior to contacting one another in the reactor. Such preheating step is preferably carried out after the reactants have been raised to the pressure at which the reaction is to be effected. Any suitable form of preheater may be employed, and the two preheaters may advantageously consist of two separate coils mounted in a common vessel containing a suitable liquid or gas maintained at a suitable temperature. The reactor may likewise advantageously comprise a coil immersed in a liquid or gaseous medium heated to a suitable temperature. It will be apparent that the design of the reactor will be determined by the velocity at which the reactants pass therethrough and the period of time over which it is desired that they remain in the reaction zone. The flow of the respective reactant streams to the reaction zone is in each case adjusted in accordance with the concentration of the reactant so that from about 0.75 to about 2.0 mols of nitrogen tetroxide are provided for each mole of cyclo-mono-olefine. By employing mole ratios of this order, together with the previously mentioned short contact time, side reactions, as for example substitution and oxidation reactions and reactions between the nitrogen tetroxide and the solvent, are minimized.

The reaction product withdrawn from the reactor may contain a small amount of water and water-soluble by-products as well as small quantities of gas. Accordingly, it is desirable that the entire product be quickly cooled to a temperature below that at which further reaction takes place, and then treated to separate the organic products from any aqueous phase and/or non-condensed gases. Such treatment may com-

prise simple gravity settling whereby the aqueous phase is separated as a subnatant layer, or it may involve other means of separation such as absorption, selective solvent extraction, or treatment with a dehydrating agent. In some cases the nature of the product and its subsequent purification is such that the separation step may be omitted entirely.

The crude nitration product is finally treated to separate the saturated hydrocarbon solvent, and such treatment will usually also comprise separation of the different nitrated products formed in the reaction. The separation treatment may comprise a conventional fractional distillation, as is shown in the accompanying drawing, although other separation methods, such as crystallization, solvent extraction, azeotropic distillation, etc. may be employed if desired.

The following example will illustrate several ways in which the principle of the invention has been applied, but is not to be construed as limiting the same. All proportions are given in parts by weight.

Example

Approximately 1770 parts of a 17.4 per cent solution of nitrogen tetroxide in cyclohexane was passed at a rate of about 69 parts per minute and under a pressure of 200 p. s. i. g. through a preheater which consisted of an 18-inch long stainless coil immersed in a liquid bath maintained at a temperature of about 165° C. From the preheater the solution was passed directly into a reactor which consisted of a 10-foot coil of $\frac{1}{4}$ -inch stainless steel tubing immersed in a liquid bath maintained at a temperature of about 160° C. A cooled receiver was attached to the reactor coil so that the products issuing therefrom were immediately cooled to approximately room temperature. Simultaneously, 1375 parts of a 20.7 per cent solution of cyclohexene in cyclohexane was passed at a rate of about 58.5 parts per minute and under a pressure of about 200 p. s. i. g. through a similar preheater maintained at a temperature of 168° C. and into the reactor where it contacted the stream of nitrogen tetroxide solution. The respective rates of flow were such that the mole ratio of nitrogen tetroxide to cyclohexene was about 0.97/1.0 and the time of passage through the reactor was about 0.26 minute. Upon completion of the run, approximately 3102 parts of liquid product were recovered from the receiver. This product was steam-distilled without further treatment, whereby there was recovered 2346 parts of cyclohexane, an intermediate cut amounting to 21 parts, and 465 parts of a bottoms fraction comprising for the most part 1,2-dinitrocyclohexane and nitrite-nitrocyclohexane. Based on the amount of cyclohexene taken, the yield of nitrogen oxide addition products was about 74 per cent of theoretical.

The nitrogen oxide addition products prepared as described herein have varied uses in the arts. They are valuable chemical intermediates in the preparation of other chemical products, and may be employed as additives for various types of liquid hydrocarbon fuels, e. g., diesel fuel, jet propellants, etc.

Other modes of applying the principle of our invention may be employed instead of those explained, change being made as regards the methods or materials employed provided the step or steps stated by any of the following claims,

or the equivalent of such step or steps, be employed.

We, therefore, particularly point out and distinctly claim as our invention:

- 5 1. The method of making nitrogen oxide addition products of cyclo-olefines which comprises forming a solution of a cyclo-mono-olefine in a solvent consisting essentially of the cyclo-aliphatic hydrocarbon corresponding to said mono-olefine, forming a solution of nitrogen tetroxide in a solvent consisting essentially of the saturated cyclo-aliphatic hydrocarbon corresponding to said cyclo-mono-olefine, separately heating said solutions to a temperature between about 40° C. 10 and about 300° C. and under a pressure between about 2 and about 100 atmospheres sufficient to maintain the cyclo-olefine and the solvent substantially entirely in the liquid phase, combining said solutions and maintaining the combined 15 solutions at a temperature and a pressure within the aforementioned ranges for a period of time between about 0.1 and about 2 minutes, cooling the reaction product to a temperature below that at which further reaction takes place, and recovering said addition products from said cooled reaction product.
- 20 2. The method of making nitrogen oxide addition products of cyclohexene which comprises separately heating a solution of nitrogen tetroxide in cyclohexane and a solution of cyclohexene in cyclohexane to a temperature between about 30° C. and about 200° C. and under a pressure between about 2 and about 50 atmospheres sufficient to maintain the cyclohexene and the cyclohexane substantially entirely in the liquid phase, combining said solutions and maintaining said combined solutions at a reaction temperature between about 80° C. and about 200° C. and under a pressure between about 2 and about 20 atmospheres sufficient to maintain the cyclohexene and the cyclohexane substantially entirely in the liquid phase for a period of time between about 0.1 and about 2 minutes, cooling the reaction product to a temperature below that at which further reaction takes place, and recovering said addition products from said cooled reaction product.
- 25 3. The method of claim 2 wherein the nitrogen tetroxide and cyclohexene solutions contain between about 5 and about 25 per cent by weight of nitrogen tetroxide and cyclohexene, respectively.
- 40 4. The method of claim 2 wherein the nitrogen tetroxide and cyclohexene are employed in substantially equimolecular proportions.
- 45 5. The method of making nitrogen oxide addition products of cyclohexene which comprises continuously passing solutions of nitrogen tetroxide and cyclohexene in cyclohexane through separate preheating zones and into a common reaction zone, the temperature within said preheating and reaction zones being maintained between about 80° C. and about 200° C. and the pressure within said preheating and reaction zones being maintained between about 2 and about 20 atmospheres and being sufficient to maintain the cyclohexene and the cyclohexane substantially entirely in the liquid phase, continuously passing said solution through said reaction zone at such a rate that the residence time within said reaction zone is between about 0.1 and about 2 minutes, continuously withdrawing a reaction product from said reaction zone and cooling said reaction product to a temperature below that at which further reaction takes place, and recovering said addition products from said reaction product.
- 50 6. The method of claim 5 wherein the nitrogen tetroxide and cyclohexene are employed in substantially equimolecular proportions.
- 55 7. The method of making nitrogen oxide addition products of cyclohexene which comprises continuously passing solutions of nitrogen tetroxide and cyclohexene in cyclohexane through separate preheating zones and into a common reaction zone, the temperature within said preheating and reaction zones being maintained between about 80° C. and about 200° C. and the pressure within said preheating and reaction zones being maintained between about 2 and about 20 atmospheres and being sufficient to maintain the cyclohexene and the cyclohexane substantially entirely in the liquid phase, continuously passing said solution through said reaction zone at such a rate that the residence time within said reaction zone is between about 0.1 and about 2 minutes, continuously withdrawing a reaction product from said reaction zone and cooling said reaction product to a temperature below that at which further reaction takes place, and recovering said addition products from said reaction product.
- 60 8. The method of claim 7 wherein the nitrogen tetroxide and cyclohexene are employed in substantially equimolecular proportions.
- 65 9. The method of claim 5 wherein the nitrogen tetroxide and cyclohexene are employed in substantially equimolecular proportions.
- 70 10. The method of claim 5 wherein the nitrogen tetroxide and cyclohexene are employed in substantially equimolecular proportions.
- 75 11. The method of claim 5 wherein the nitrogen tetroxide and cyclohexene are employed in substantially equimolecular proportions.

6. The method of claim 5 where in the nitrogen tetroxide and cyclohexene are employed in substantially equimolecular proportions.

7. The method of claim 5 wherein the nitrogen tetroxide and cyclohexene solutions contain between about 5 and about 25 per cent by weight of nitrogen tetroxide and cyclohexene, respectively.
